UNITED STATES PATENT OFFICE.

OLIVER M. EVANS, OF BREWSTER, OHIO.

CUSPIDOR LIFTER AND CARRIER.

1,147,316.

Specification of Letters Patent.

Patented July 20, 1915.

Application filed November 16, 1914. Serial No. 872,338.

To all whom it may concern:

Be it known that I, OLIVER M. EVANS, a citizen of the United States, residing at Brewster, in the county of Stark and State 5 of Ohio, have invented certain new and useful Improvements in Cuspidor Lifters and Carriers, of which the following is a specification.

My invention relates to improvements in 10 cuspidor lifters and carriers in which a frame is provided, made up of a series of bars spaced apart and formed in pairs, the pairs of bars being movable with reference to each other.

15 The objects of the present invention are, first, to provide a simple device whereby a single cuspidor can be lifted and carried or a number of cuspidors can be lifted and carried, second, to provide for the movement 20 of the pairs of bars whereby the cuspidors can be clasped and released.

These objects, together with other objects readily apparent to those skilled in the art may be attained by the construction illustrated 25 in the accompanying drawing, although the invention may be embodied in other forms the construction illustrated being chosen by way of example.

In the accompanying drawings: Figure 30 1 is a perspective view. Fig. 2 is a side elevation showing a number of cuspidors properly arranged and in position to be lifted and carried. Fig. 3 is an edge view.

Similar numerals of reference indicate 35 corresponding parts throughout all the figures of the drawing.

In the accompanying drawing, 1 represents the pivoted lift-bars, which are formed in pairs, the bars of each pair are held together and in proper spaced relationship with reference to each other by means of the upper or top tie bars 2 and the grip or holding bars 3, said tie and grip bars being riveted or otherwise attached, the attachment 40 being such that a rigid connection will be made as between the lift bars 1 and the tie and grip bars 2 and 3. The top or upper ends of the lift bars 1 are pivotally connected, said pivotal connection being such that the opposite pairs of lift bars are free to turn upon their pivotal points, thereby allowing the bottom or lower ends of the lift bars 1, together with the grip bars 3 to come and go to and from each other. To 45 the lift bars 1 are pivotally connected the links 5 which links are pivoted together at

their inner ends and to said inner ends are also pivotally connected the sliding bars 6. For the purpose of properly guiding the movements of said sliding bars the head 60 bars 4 are provided with the plates 7, which plates are securely connected to the head bars 4 in any convenient and well known manner. The plates 7 should be so formed that they will properly embrace and hold 65 the sliding bars 6. It will be understood that the exact arrangement of the plates 7 is immaterial, as the only object is to provide means for properly guiding the sliding bars 6 and holding said bars in proper 70 relative position.

To the top or upper ends of the sliding bars 6 is attached the carrying handle 8. Directly below the handle 8 is located the bar 9, which bar is so arranged that it can 75 be grasped by the hand or fingers when the hand is placed upon the handle 8, so that a downward pressure upon the handle 8 or a pull upon the bar 9 will force the handle toward the bar 9, thereby imparting longitudinal movement to the sliding bars 6 which in turn moves the pairs of bars 1 outward at their bottom or lower ends by means of the links 5 being pivotally connected to said sliding bars 6 and to each other, by 80 which pivotal arrangement a toggle joint is produced, as between the sliding bars 6 and links 5. It will be understood that the bars 9 are to be securely connected to the top or head bars 4 so that there can be no relative 85 movement as between the bar 9 and the head bars 4. The grip or lifting bars 3 should be curved as illustrated in Fig. 1, by which arrangement the cuspidors will be better held against displacement when the grip 90 bars are brought into contact with the cuspidors. In use the handle 8 and the bar 9 are grasped by the hand and fingers, at which time the handle 8 can be forced toward the bar 9 either by a pull upon the bar 9 or a push upon the handle 8. Said push or pulling action will move the lower ends of each pair of the lifting bars 1 together with the grip bars 3 away from each other and bring them in such relationship with reference to each other that they can be placed upon opposite sides of a cuspidor, after which an upward pull of the handle 6 will draw the grip bars, together and into position to embrace and clamp or grip a cuspidor. 100

110

In case it is desired to lift or carry a num-

ber of cupidors, each cupidor can be picked up one at a time as for instance a single cupidor can be gripped and placed on top of another cupidor and another one gripped 5 and so until the capacity of the carrier has been exhausted.

For the purpose of providing room for the top or uppermost cupidor when a number of cupidors are to be carried as illustrated in Fig. 2, the links 5 should be curved 10 so that the proper amount of room will be provided for the funnel portion of the cupidor.

It will be noticed that each of the grip or 15 holding bars 3 is provided near either extremity and upon the inner face with a button or lug 10 formed of rubber or some similar material. By means of these buttons it will be possible to obtain a better grip upon 20 a cupidor.

Although the drawings and above specification disclose the best mode in which I have contemplated embodying my invention I desire to be not limited to the details of such 25 disclosure, for, in the further practical application of my invention, many changes in form and construction may be made, as circumstances require or experience suggests, without departing from the spirit of the invention, within the scope of the appended 30 claims.

Having fully described my invention what I claim as new and desire to secure by Letters Patent, is—

35 1. In a device of the character described, the combination of lifting bars formed in pairs, top bars adapted to hold the top or upper ends of the pairs of lifting bars in spaced relationship with reference to each 40 other, said lifting bars pivotally attached to said top bars, links pivotally connected to the pairs of lifting bars and to each other, sliding bars pivotally connected to the links, a handle connected to said sliding bars and a 45 fixed bar located directly below the handle and grip bars connected to the bottom or lower ends of the lifting bars.

2. In a device of the character described, the combination of lifting bars formed in

50 pairs, top bars adapted to hold the top or upper ends of the pairs of lifting bars in spaced relationship with reference to each other, said lifting bars pivotally attached to said top bars, curved links pivotally connected to the pairs of lifting bars and to each 55 other, sliding bars pivotally connected to the curved links, a handle connected to said sliding bars and a fixed bar located directly below the handle and grip bars connected to the bottom or lower ends of the lifting bars. 60

3. In a device of the character described, the combination of lifting bars formed in pairs, top bars adapted to hold the top or upper ends of the pairs of lifting bars in spaced relationship with reference to each 65 other, said lifting bars pivotally attached to said top bars, links pivotally connected to the pairs of lifting bars and to each other, sliding bars pivotally connected to the links, a handle connected to said sliding bars, and a fixed bar located directly below the handle, grip bars connected to the bottom or lower ends of the lifting bars, and lugs formed of friction material located upon the inner 70 faces of said grip bars. 75

4. In a device of the character described, the combination of lifting bars formed in pairs, top bars adapted to hold the top or upper ends of the pairs of lifting bars in spaced relationship with reference to each 80 other, said lifting bars pivotally attached to said top bars, curved links pivotally connected to the pairs of lifting bars and to each other, sliding bars pivotally connected to the curved links, a handle connected to 85 said sliding bars and a fixed bar located directly below the handle, grip bars connected to the bottom or lower ends of the lifting bars, and lugs formed of friction material located upon the inner faces of said grip bars. 90

In testimony that I claim the above, I have hereunto subscribed my name in the presence of two witnesses.

OLIVER M. EVANS.
